Attorney

UNITED STATES PATENT OFFICE.

JOHN G. HERNDON, OF MARSHALL, MISSOURI.

WIRE STRETCHER.

Application filed July 13, 1923. Serial No. 651,422.

To all whom it may concern:

Be it known that I, JOHN G. HERNDON, a citizen of the United States, residing at Marshall, in the county of Saline and State 5 of Missouri, have invented certain new and useful Improvements in a Wire Stretcher, of which the following is a specification.

This invention relates to tools used in wire fence work and one of the primary objects 10 of the invention is to provide an improved combination tool, which is particularly adapted for stretching line wire and for use as a single lever stretcher for bringing the wire about an end post, after the wire has 15 been attached to the intermediate posts.

Another prime object of the invention is to provide an efficient wire stretching tool embodying a pair of pivotally connected rack bars and an operating and wire stretching lever adapted to be moved in a step by 20 step movement along said bars, the lever being detachably associated with the rack bars, whereby the same can be used as a single lever for stretching the wire.

25 A still further object of the invention is to provide an improved combination wire stretching tool of the above character, which will be durable and efficient in use, one that will be simple and easy to manufacture and 30 one which can be placed upon the market at a reasonable cost.

With these and other objects in view, the invention consists in the novel construction, arrangement and formation of parts as will 35 be hereinafter more specifically described, claimed and illustrated in the accompanying drawings, in which drawings:

Figure 1 is a perspective view of the improved tool, showing the same in use for 40 stretching a line wire.

Figure 2 is a detail perspective view showing the operating lever used as a single lever wire stretcher.

Figure 3 is a top plan view of the operating lever, showing the same used as a single lever wire stretcher.

Figure 4 is an enlarged detail perspective view of the wire holding dog or clamp.

Figure 5 is a transverse section through 50 the improved wire stretching tool showing the operating lever in edge elevation.

Figure 6 is a fragmentary plan view illustrating the construction of one of the rack bars in detail.

Figure 7 is a detail transverse section 55 through the operating lever taken on the line 7-7 of Figure 5.

Referring to the drawings in detail, wherein similar reference characters designate corresponding parts throughout the 60 several views, the letter A generally indicates the improved wire stretching tool, which comprises a pair of elongated bars 10 and 11. These bars are provided at their 65 inner ends with oppositely extending right angularly disposed arms 12 and 13 respectively. As clearly shown in Figures 1 and 6 of the drawings the bars 10 and 11 are pivotally connected together by means of a pin 14 at the point of connection of the 70 arms 12 and 13 therewith. The terminals of the arms 12 and 13 receive short chains 15 and 16 which are connected to a common eye 17. The eye 17 in turn carries an attaching chain 18, which is adapted to be 75 brought about a suitable post or other anchored member 19 and the free end thereof is adapted to be secured to the ring 17 by means of a hook 20 carried thereby. The 80 outer edges of the bars 10 and 11 are provided with rack bars 21 and 22 respectively, each of which consist of a plurality of notches or teeth. As clearly shown in Figure 1 of the drawings the outermost teeth of the arms 10 and 11 are provided with 85 relatively deep notches 23 for a purpose, which will be hereinafter more fully described.

Mounted upon the bars 10 and 11 is the operating lever 25 which in connection with 90 the bars form means for stretching a line wire designated by the reference character B. The inner end of the lever 25 is provided with a guide strap 26 through which the bar 10 is adapted to be detachably 95 placed. The outer end of the guide strap 26 is secured to the inner end of the lever as at 27 and the inner end of the lever and the outer end of the strap are cut an angle as at 28 to provide a sharpened fulcrum 100 point 29, for a purpose, which will also be hereinafter more fully described. The inner end of the guide strap 26 is secured to the lever 25 by means of a spacing block 30 which also forms a part of the wire holding means, as will be hereinafter more fully 105 apparent.

A pin 31 extends through the guide strap

26 and lever 25 for engaging the teeth of the rack bar 21 in order to permit the lever to be advanced along the rack bars in a step by step movement. A second guide strap 32 is disposed inwardly of the guide strap 26 and is secured as at 33 to the body portion of the lever. The end of the guide strap 32 which is spaced from the lever 25 carries a pin 34 which is adapted to engage the rack bar 22 of the lever 11 for permitting the advancement of the said lever along the rack bars. This pin 34 also forms a pivot for the wire holding dog or clamp 35, which is clearly shown in detail in Figure 5 of the drawings. This wire engaging clamping dog 35 is of a substantial bell crank configuration and the bolt 34 passes through an opening 36 formed in the angle thereof. One end of the dog 35 is provided with wire biting teeth 37 which are arranged in an arcuate line, so that as the tension on the wire is increased, the dog will tend to bite more firmly into the wire and force the same in tighter contact with the spacing block 30. The opposite end of the dog forms a thumb piece for permitting the manipulation thereof by the thumb of the user.

It is also to be noted at this point that the teeth or notches of the rack bars 21 and 22 at the inner ends of the bars 10 and 11 are formed less in depth than the notches at the outer ends of the bars, and this prevents the weakening of the bars at a point, where the greatest stress occurs thereon during the stretching of the wire.

The bar 11, which works between the wire holding dog 35 and the guide strap 32, is pivoted on top of the opposite bar 10. This makes the bars and the lever line up true. In use of the tool for stretching line wire, the chain 18 is hooked about the post or other anchored member 19 and the operating lever is placed upon the bars 10 and 11 with the pins 31 and 34 in engagement with the deep end notches 23 which holds the lever against displacement. Now the wire B is placed in engagement with the outer face of the block 30 and the thumb of the user is placed upon the outer end of the dog so as to move the teeth 37 formed thereon into intimate contact with the wire B. The lever is now swung backward and forward so as to first move the pin 31 into engagement with the next adjacent tooth of the rack bar 22. This operation is continued and the lever moves along the rack bars 21 and 22 in a step by step movement which brings about the easy stretching of the line wire. After the wire is stretched, the same is secured to the fence post in any preferred way after which the dog is moved from out of engagement with the wire by means of inward pressure by the thumb of the user on the outer end of the dog 35.

The lever 25, can be used by itself for

effectively stretching the wire, to permit the same to be secured to the end post or permit the wire to be brought around an end or corner post. When the lever is used by itself for this purpose, the wire to be stretched is secured to the lever in the same manner as heretofore described, while the sharpened fulcrum point 29 is placed in engagement with the end or corner post and the lever is swung on this point, which will effectively stretch the wire and permit the same to be easily secured to the post.

From the foregoing description it can be seen that I have provided an exceptionally simple and durable wire stretcher which can be effectively used for both stretching line wires and for permitting the connection of the wire to an end or corner post.

Changes in details may be made without departing from the spirit or the scope of this invention.

What I claim as new is:

1. A wire stretching tool comprising a pair of pivotally connected rack bars angularly extending arms formed on the rack bars, and arranged outwardly of the pivot of the rack bars, an anchoring chain connected to the outer terminals of the arms, an operating lever mounted upon the rack bars for movement thereover step by step, and a wire clamp carried by the lever for receiving the line wire to be stretched.

2. A wire stretching tool comprising a pair of members each including a longitudinally extending bar having teeth formed on the outer edge thereof and a right angularly disposed arm, means connecting the members together at their angle for swinging movement, anchoring chains connected to the outer terminals of the arms for normally swinging the bars away from each other, an operating lever, guides carried by the operating lever for receiving the bars, means carried by the guides for engaging the teeth, on said bars, the lever being adapted for a step by step movement over said bars, and a wire clamp carried by the lever.

3. A wire stretching tool comprising a pair of L-shaped members each including an elongated bar and a right angularly disposed arm, the bars having rack teeth formed on their outer longitudinal edges, means pivotally connecting the members together at their angles, attaching chains connected to the outer terminals of the arms for connection with an anchored member and for normally swinging the bars away from one another, an operating lever, a pair of spaced guides mounted upon the lever for receiving said bars to permit the sliding association of said lever with the bars, pins carried by the guides for engaging the teeth on said bars, a block, an angle-shaped dog pivotally secured at its angle between the guides, and wire biting teeth formed on the

active end of the dog for engaging and forcing the wire to be stretched in engagement with said block.

4. A wire stretching tool comprising a pair of pivoted rack bars, means connecting the rack bars to an anchored member, an operating lever slidably mounted upon the rack bars, pins carried by the lever for engaging the teeth of the rack bars, and a wire clamp carried by the lever, the outermost

teeth of the rack bars being formed relatively deep to form seats for the pins to permit the convenient initial attachment of the wire to be stretched to said clamp.

In testimony whereof I affix my signature **15** in presence of two witnesses.

JOHN G. HERNDON.
